US00D635681S

(12) **United States Design Patent**
Edwards et al.

(10) **Patent No.:** **US D635,681 S**
(45) **Date of Patent:** **** Apr. 5, 2011**

(54) **PATIENT-MONITOR HOUSING**

(75) Inventors: **Ian K Edwards**, Skaneateles, NY (US);
Shawn St. Pierre, Syracuse, NY (US);
Thaddeus J Wawro, Auburn, NY (US);
Scott A Martin, Warners, NY (US);
Adam Leonards, El Cerrito, CA (US);
Alex Millie, San Francisco, CA (US)

(73) Assignee: **Welch Allyn, Inc.**, Skaneateles Falls, NY (US)

(**) Term: **14 Years**

(21) Appl. No.: **29/366,255**

(22) Filed: **Jul. 22, 2010**

(51) LOC (9) Cl. **24-01**

(52) U.S. Cl. **D24/186**

(58) Field of Classification Search D24/107, D24/111, 164-165, 168-169, 185-186, 167; 600/301, 481, 483-485, 509, 513, 519, 544; 128/900; D10/81, 104; D14/381, 126, 371

CLAIM

The ornamental design for a patient-monitor housing, as shown and described.

DESCRIPTION

FIG. 1 is a top perspective view of the patient-monitor housing showing our new design;

FIG. 2 is a bottom perspective view of the patient-monitor housing shown in FIG. 1;

FIG. 3 is a front view of the patient-monitor housing shown in FIG. 1;

FIG. 4 is a rear view of the patient-monitor housing shown in FIG. 1;

FIG. 5 is a top view of the patient-monitor housing shown in FIG. 1;

FIG. 6 is a bottom view of the patient-monitor housing shown in FIG. 1;

FIG. 7 is a right-side view of the patient-monitor housing shown in FIG. 1; and,

FIG. 8 is a left-side view of the patient-monitor housing shown in FIG. 1.

The broken lines shown herein are for illustrative purposes only and form no part of the claimed design. The unshaded portions and seam lines shown in broken lines form no part of the claimed design.

1 Claim, 5 Drawing Sheets
